J. A. ROUGE

THREAD GUIDE AND CLEANER FOR SPINNING LOOMS AND THE LIKE MACHINES

Filed July 28, 1927

Inventor:
Joseph. Auguste. Rouge.

Attorney:
Frank A. Klemm
Atty.

UNITED STATES PATENT OFFICE.

JOSEPH AUGUSTE ROUGE, OF REMIREMONT, FRANCE.

THREAD GUIDE AND CLEANER FOR SPINNING LOOMS AND THE LIKE MACHINES.

Application filed July 28, 1927, Serial No. 209,125, and in France August 4, 1926.

The present invention has for its object a thread guide and cleaner intended to eliminate from the textile staples or threads the irregularities (knots and the like) in the 5 spinning looms or the like machines in which the moving thread is submitted to a guiding action.

Until now the guiding of the thread is obtained by passing the latter between two rollers or through a simple reel; this guiding is 10 insufficient for cleaning and picking the thread. In order to allow a satisfactory cleaning, it is needful that the thread runs through a well limited space, so that a well 15 determinated section of same may pass, whereas any exceeding or projecting portion of the section or any impurity is stopped and retained.

According to the present invention I attain 20 this object in making use of a thread guide made of a wire of round section, rolled up according to curves partially disposed in parallel relation to each other and forming between them free interstices having exactly 25 the size of the sections of the textile threads intended to run through said guides.

As shown by way of example in the accompanying drawing, the thread guide is formed of a wire of round section provided with a 30 substantially straight tail (1) slightly bent at (2), then curved according to a first complete curve (3), the wire, at the end of the curve (3) being slightly bent upwards at (4), forming a second curve substantially in the 35 plane of the first curve (3), this second curve ending into a bend (6) ending by a tail (7). Two, three or more of such curves may be used.

Between the succeeding curves is provided 40 a space (8), exactly corresponding to the section of the textile thread (9) to be cleaned. The bent portion or knee (2) where the thread enters the device, is shaped so that the textile thread may exactly pass between the 45 curves, without any play with respect to the curvature in the direction of the tail (7), in

order to prevent any possibility of enlarging fraudulently the opening between the curves (space 8) and allow the passage of irregularities or projections carried by the thread. 50

The above described thread guide is located at the same places and in the same way as the guides used until now (reels).

The space (8) may vary according to the dimensions of the thread to be obtained, from 55 one tenth of a millimeter up to several millimeters.

Having now fully described my said invention, what I claim and desire to secure by Letters Patent, is:

1. A guide and cleaner for threads comprising a member consisting of a length of wire shaped to form concentric and parallel convolutions in spaced relation to one another, the spaces between the said convolutions corresponding to the size of a thread to be guided and cleaned. 65

2. A guide and cleaner for threads comprising a member consisting of a length of wire shaped to form concentric and parallel 70 convolutions in spaced relation to one another, the spaces between the said convolutions corresponding to the size of a thread to be guided and cleaned, and a guide at the ends of the member.

3. A thread guide and cleaner, a member comprising a wire of circular cross section having curved portions concentric and substantially parallel with respect to and in spaced relation to one another, the space between the concentric portions corresponding to the size of thread to be guided and cleaned, the said member terminating at one end in a curved formation in such relation to one of the concentric portions that the space between the said two parts of the guide cannot be increased without moving the concentric portions of the guide closer together. 85

In testimony whereof I have hereunto set my hand.

JOSEPH AUGUSTE ROUGE.
